UNITED STATES PATENT OFFICE.

FRIDOLIN SCHIMMEL, OF FARIBAULT, MINNESOTA.

DESIGN FOR A SPINET-DESK BODY.

Application filed March 31, 1927. Serial No. 21,417. Term of patent 3½ years.

To all whom it may concern:

Be it known that I, FRIDOLIN SCHIMMEL, a citizen of the United States, residing at Faribault, in the county of Rice and State of Minnesota, have invented a new, original, and ornamental Design for Spinet-Desk Body, of which the following is a specification, reference being had to the accompanying drawing, forming part thereof.

The single view of the drawing is a perspective of a spinet desk body, showing my new design.

I claim:

The ornamental design for a spinet desk body, as shown.

FRIDOLIN SCHIMMEL.
